UNITED STATES PATENT OFFICE.

HENRY L. SNEDAKER, OF BINGHAMTON, NEW YORK.

LATCH FOR TRUNKS AND THE LIKE.

1,163,569.

Specification of Letters Patent.

Patented Dec. 7, 1915.

Application filed May 18, 1915. Serial No. 28,931.

To all whom it may concern:

Be it known that I, HENRY L. SNEDAKER, a citizen of the United States, residing at Binghamton, in the county of Broome, State of New York, have invented certain new and useful Improvements in Latches for Trunks and the like; and I do hereby declare the following to be a full, clear, and exact description of the invention, such as will enable others skilled in the art to which it appertains to make and use the same.

This invention relates to new and useful improvements in latches particularly adapted for use on suitcases or trunks or the like, and is particularly directed to the provision of a latch structure wherein a positive lock is procured to prevent accidental displacement of the latch.

It is the object of the present invention to provide an improved latch of the class described which is provided with means for locking the plate members of the latch together and which is also provided with a hasp member of conventional type which serves to perform its normal function of holding the members of the latch, and which at the same time forms a shield for the said positive locking means.

A further object is to provide such a latch which may be readily operated, and which is of relatively simple structure so as to permit manufacture at a comparatively low cost.

With the above and other objects and advantages in view, the invention resides more particularly in the novel combination, formation and arrangements of parts as more fully described hereinafter and pointed out in the appended claims.

Reference is had to the accompanying drawings, wherein similar characters of reference designate corresponding parts throughout the several views, and in which:

Figure 1 is an elevation view of the improved latch member. Fig. 2 is a side view of the structure shown in Fig. 1. Fig. 3 is a central vertical sectional view through the latch. Fig. 4 is a detail perspective of the main keeper member of the latch.

Referring now more particularly to the accompanying drawings, the improved device is shown as comprising a hasp member comprising a plate 5 for attachment to the body of the receptacle and a guide member

or casing 6 thereon open at one end and having pivoted thereto the loop 7 forming the hasp proper. A spring 8 of conventional type is disposed in this casing and engages the adjacent portion of the hasp member to resiliently hold it in either limit of pivotal movement.

A keeper plate 9 for attachment to the cover of the receptacle is provided, and this keeper plate has a tongue 10 at one of its side edges adapted to extend into the open end of the guide casing 6, and this plate is further provided with a keeper block 11 which is riveted or otherwise secured thereto to hold the hasp loop. This is the conventional latch structure. To provide a more positive locking means coöperating with this structure, the plate 5 is provided within the guide casing with a transverse slot 12, and the free end of the tongue 10 of the keeper plate is bent laterally at 13 to engage in this slot, the tongue being permitted a certain lateral movement in the open end of the casing whereby its portion 13 may be retracted. The tongue is adapted to be locked against such lateral movement by a substantially U shape member 14 having its arms slidably passed through the keeper block and engageable in the open end of the guide casing, the free ends of the arms being beveled as at 14' to facilitate their insertion should the open end of the casing be slightly out of alignment. This U shape member is guided during its movement by a lug 15 slidably in a groove 16 in the keeper plate. This whole structure is assembled and held in assembled position by securing the block 11.

A comparatively simple device has thus been provided which may be very readily operated, and which efficiently and positively holds the latch locked. The use of the conventional hasp loop 7 serves to relieve the strain on the tongue 10, and further serves when in locking position as guard to prevent the holding member 13 against being struck and knocked out of place, the free end of the hasp loop being widened to form a finger grip.

What is claimed is:

1. A latch member comprising a plate, formed with a slot, a guide member adjacent the slot, a second plate, a tongue on the second plate engageable in the guide member and having one end laterally directed to extend into the slot, and a holding member

slidably mounted to extend between the guide member and the tongue to lock said laterally directed portion in the slot.

2. A latch member comprising a plate, 5 formed with a slot, a guide member adjacent the slot, a hasp loop pivoted to the plate a second plate, a tongue on the plate engageable in the guide member and having its end laterally directed to extend into the 10 slot, a keeper block on the second plate and

a holding member slidably held by the keeper block and engageable in the keeper to lock the tongue against movement.

In testimony whereof, I affix my signature, in the presence of two witnesses.

HENRY L. SNEDAKER.
